HAND CULTIVATING TROWEL

Joseph J. Greiner, Arlington, Va.

Application June 30, 1955, Serial No. 36,765

Term of patent 14 years

(Cl. D39—1)

Fig. 1.

Fig. 2

Fig. 3.

Fig. 4.

Fig. 1 is a side elevational view of a hand cultivating trowel showing my new design;

Fig. 2 is a top plan view;

Fig. 3 is a rear end view; and

Fig. 4 is a front end view thereof.

I claim:

The ornamental design for a hand cultivating trowel, as shown.
